L. W. BELL,
GRAIN RECOVERY ATTACHMENT FOR THRASHING MACHINES,
APPLICATION FILED SEPT. 19, 1921.

UNITED STATES PATENT OFFICE.

LORENZO W. BELL, OF CARROLLTON, MISSOURI, ASSIGNOR, BY DIRECT AND MESNE ASSIGNMENTS, TO NATIONAL GRAIN SAVERS ASSOCIATION, OF CARROLLTON, MISSOURI.

GRAIN-RECOVERY ATTACHMENT FOR THRASHING MACHINES.

1,412,383.

Specification of Letters Patent. Patented Apr. 11, 1922.

Application filed September 19, 1921. Serial No. 501,763.

To all whom it may concern:

Be it known that I, LORENZO W. BELL, a citizen of the United States, residing at Carrollton, in the county of Carroll and

5 State of Missouri, have invented a certain new and useful Improvement in Grain-Recovery Attachments for Thrashing Machines, of which the following is a complete specification.

10 This invention relates to grain-recovering apparatus, and more especially to attachments for use with pneumatic stackers, and is designed particularly as an improvement in the apparatus disclosed by United States

15 Letters Patent No. 1366899, February 1, 1921, and my object is to produce an attachment more thorough and efficient than the patented one referred to, and in which the

20 blast of air from the pneumatic stacker tube shall, in conjunction with one or more screens, accomplish the separation of loose grain from the straw, by imparting a distinct and forcible jolt to the straw, as distinguished from the patented apparatus in

25 which gravity alone is depended upon to insure such separation of the grain from the straw and chaff.

With the object named in view the invention consists in certain novel and useful features of construction and organization of parts as hereinafter described and claimed; and in order that it may be fully understood, reference is to be had to the accompanying drawing, in which:

35 Figure 1 is a side view of a pneumatic stacker with the device of the invention in operation thereto.

Figure 2 is an enlarged central vertical section through the invention and the end of the stacker.

40 Figure 3 is a section on the line III—III of Figure 1.

Figure 4 is a section on the line IV—IV of Figure 2.

45 Figure 5 is an enlarged central vertical section of the delivery end of the apparatus.

In the said drawing where like reference characters identify corresponding parts in all of the figures, 1 indicates a pneumatic stacker tube of any common and well-known type. Adjustably embracing the stacker at any convenient points are a pair of clamping rings 2 which carry and secure in posi-

tion on the stacker a relatively rectangular shaped chute 3 which projects some distance 55 beyond the end of the stacker as shown in the drawing.

Pivoted in the end of chute 3 is a hood composed of a pair of side members 4 and a relatively J-shaped connecting member 5 60 (see Figure 2). The open side of the hood is closed by a plate 6 forming a receiving mouth 7 for the end of the hood. It will be noted that the small end of the hood projects slightly into the chute in order that no grain 65 shall be lost as will hereinafter appear.

70 Journalized on a shaft 8 connecting the sides 4 of the hood is a fan 9 adapted to be rapidly rotated by the force of the air blast exerted by the blower of the stacker as will be readily understood, and adapted to act as a gate and prevent the dropping downward of grain and to also propel it forcefully through the hood into the chute through centrifugal force.

75 Secured rigidly to the chute on the underside thereof are a pair of screens 10 and 11, composed of a series of parallel rods, the former somewhat closer together than the latter, against which the straw ejected by the stacker is adapted to be projected with considerable force and jolt the grain from position, when through the combined action of the air blast and the wheel 9, it will be caught and thrown through the hood and 80 down the chute 3. In order to provide means for adjusting the angle at which the straw shall strike the screens a pair of arms 12 are secured to the chute and depend downwardly therefrom adjacent the mouth 85 of the stacker, and pivotally secured at their lower ends is a deflector 13 provided with a pair of sides 14, so that the straw shall not be thrown sideways or drop directly downwardly.

90 95 A pair of triangular shaped guards 15 are secured to the chute and hood in such a manner that there is no chance for the straw to be pitched sideways after striking the deflector as will be readily apparent by reference to the drawing.

The chute 3 tapers at its lower end as at 16 and is connected to a flexible cylindrical telescopic down chute 17, depending at its lower end into a hopper 18 carried by the 100 105 thresher by means of an arm 19. Chute 17

is made flexible in order that it may accommodate the swinging movements of the stacker under operative conditions.

An inclined screen 20 of sufficiently fine mesh to permit the somewhat heavy grain to pass through but which will prohibit the passage of the small amount of light chaff and small bits of straw which may enter the hopper with the grain, is secured near the lower end of the hopper, and in order to provide means for the escape of this straw and chaff, the hopper at the low side of the screen is formed with an opening 21, the lower margin of which is provided with a lip 22 to prevent any grain from being blown out with the chaff as will be readily understood. The recovered grain after its passage through the screen will descend through a spout 23 into a sack or other container.

In order that the position of the hood may be adjusted to correspond with the changes in position of the stacker, a bracket 24 is secured to the upper side thereof, and pivoted to the end of said bracket is a rod 25 leading downwardly and rearwardly and pivotally secured to a lever 26 provided with a releasable dog for engagement with the teeth of a toothed segment 27 secured rigidly in position on the stacker 1 by means of a clamp ring 28. It will be apparent that by this mechanism, the angle of the hood may be altered at will, depending upon the height of the stacker and various other conditions, such as the weight of the straw or the force of the air blast.

It is not believed that further recapitulation of the operation of the device is necessary other than to state that it is the heavy jolt given the straw as it is projected from the stacker against the deflector 15 and then against the screens 10 and 11 which causes the heavy grain to be loosened from the straw and chaff and to continue its course in substantially the same direction as when projected from the stacker. The grain being small in size will pass through the screens and into the openings 7 where it will together with the force of the air blast cause fan 9 to rapidly rotate. The rotation of fan 9 will be sufficiently rapid to throw the grain through the hood into the mouth of the chute 3 down which it will slide both under the action of gravity and the force of the air blast as will be readily understood. The grain will finally fall through screen 20 while the light straw and chaff will be blown through the opening 21.

From the above description it will be apparent that I have produced a device of the character described, which possesses all of the features of advantage set forth as desirable, and while I have described and claimed the preferred embodiment of the same, I reserve the right to make all changes properly falling within the spirit and scope of the appended claims.

I claim:

1. The combination with a pneumatic stacker tube, of a hood projecting beyond and above the end of said tube, a chute in communication with said hood, and means interposed between said hood and tube for separating the grain from the straw.

2. The combination with a pneumatic stacker tube, of a hood projecting above and beyond the end of said tube, a chute in communication with said hood, and a series of rods interposed between said hood and chute.

3. The combination with a pneumatic stacker tube, of a hood projecting above and beyond the end of said tube, a chute in communication with said hood, means interposed between said hood and chute for separating the grain from the straw, and a deflector for directing the straw against said means.

4. The combination with a pneumatic stacker tube, of a chute carried by said tube, a hood pivotally carried by said chute and beyond and above the end of said tube, means interposed between the end of said tube and the hood for separating the grain from the straw, a deflector for directing the straw against said separating means, and guards to prevent sidewise dislodgment of the straw.

5. The combination with a pneumatic stacker tube, of a chute carried by said tube, a hood pivotally carried by said chute above and beyond the end of said tube, a fan in said hood, and means for separating the grain from the straw interposed between said hood and tube.

6. The combination with a pneumatic stacker tube, of a chute carried by said tube, a hood pivotally carried by said chute above and beyond the end of said tube, a fan in said hood, a screen interposed between said hood and the end of the tube, and a deflector adapted to direct the straw projected from the tube against said screen.

In witness whereof I hereunto affix my signature.

LORENZO W. BELL.
